UNITED STATES PATENT OFFICE.

ROBERT E. McELDOWNNEY, OF NEW MARTINSVILLE, WEST VIRGINIA, ASSIGNOR TO
NEW MARTINSVILLE GLASS MFG. CO., OF NEW MARTINSVILLE, WEST VIRGINIA,
A CORPORATION OF WEST VIRGINIA.

DESIGN FOR A BOTTLE STOPPER.

Application filed November 2, 1926. Serial No. 19,571. Term of patent 3½ years.

To all whom it may concern:

Be it known that I, ROBERT E. McELDOWNNEY, a citizen of the United States, residing at New Martinsville, county of Wetzel, State of West Virginia, have invented the new, original, and ornamental Design for a Bottle Stopper, of which the following is a specification, reference being had to the ac-

companying drawing, forming part thereof.

Figures 1 and 2 are side elevations of the bottle stopper, showing my new design.

Figure 3 is a top plan view of Figure 1.

I claim:—

The ornamental design for a bottle stopper, as shown.

ROBERT E. McELDOWNNEY.
